UNITED STATES PATENT OFFICE.

SAMUEL T. WHITAKER, OF COLUMBUS, GEORGIA, ASSIGNOR OF FIFTY-ONE ONE-HUNDREDTHS TO RALPH B. SMALL, OF COLUMBUS, GEORGIA.

CRIMPED-BOTTLE-CAP REMOVER.

1,267,153.

Specification of Letters Patent. Patented May 21, 1918.

Application filed December 18, 1915. Serial No. 67,660.

To all whom it may concern:

Be it known that I, SAMUEL T. WHITAKER, a citizen of the United States, residing at Columbus, in the county of Muscogee and State of Georgia, have invented certain new and useful Improvements in Crimped-Bottle-Cap Removers; and I do hereby declare the following to be a full, clear, and exact description of the invention, such as will enable others skilled in the art to which it appertains to make and use the same.

This invention relates to improvements in tools for removing crimped caps from bottles, and among the objects in view are reduction in expense of production, and conformity in contour of structure to the parts of the bottle for obviating the necessity for continued use of any one tool and for enabling the assemblage of a tool with a bottle in the most compact manner.

With these and further objects in view as will in part hereinafter become apparent and in part be stated, the invention comprises certain novel constructions and combinations as will subsequently be rendered clear and thereafter be particularly pointed out in the claims.

In the accompanying drawing,—

30 Figure 1 is a perspective view of a tool embodying the features of the present invention, a fragment of a bottle being indicated in dotted lines in position for the beginning of the operation of having the cap removed.

Fig. 2 is a vertical section taken on the plane indicated by line 2, 2 of Fig. 1.

Fig. 3 is a view in side elevation.

40 Fig. 4 is a plan view of the blank before the tool is completed.

Referring to the drawing by numerals, 1 indicates a strip of material, preferably sheet steel or other appropriate sheet metal, forming the body of the tool, the strip being bent at 2 to form an outstanding or overhanging portion 3, from which the main part of the body 1 depends, so that

when the tool is assembled with a bottle, the outstanding portion 3 is adapted to lie upon the upper surface of the cap of the bottle while the remainder of the body 1 depends alongside the bottle neck. A V-shaped portion is stamped from the body 1 between the edges thereof and curved to form a flange-engaging hook 4, so spaced with respect to the outstanding portion 3 as to engage the free edge of the crimped flange of the cap when the outstanding portion 3 is resting on the cap. The extremity of the outstanding portion 3 is provided with an upstanding flange 5 which is adapted to be engaged by any appropriate retaining means extending across the cap of the bottle for retaining the tool in its assembled relation with the bottle. The lower portion of the body 1 forms the handle of the tool and manipulation thereof may be somewhat facilitated by improving the gripping surface as by the provision of an aperture 6. This aperture may also be used for placing the tool on a wire or other connecting means as for purposes of shipment.

The operation will be perfectly clear and consists simply of applying the tool after the manner indicated in Fig. 1 with the outstanding portion 3 resting on the upper surface of the cap, and the hook 4 engaging beneath the flange of the cap, and then lifting upward on the lower end portion of the tool.

What I claim is:—

1. A crimped cap removing tool comprising a body of flat material bent intermediate its ends to form a right angle projecting portion for engagement with the top of the cap and having a hook extending in the same general direction as the said right angle portion and spaced from the right angle portion.

2. A crimped cap removing tool comprising a body of flat material bent to form a right angle projecting portion, and a hook stamped from the material of the body be-

tween its edges to extend generally in a direction parallel to the said right angle projecting portion.

3. A crimped cap removing tool comprising a body portion bent to form a right angle extension, a flange engaging hook portion outstanding from the body portion in the general direction of the right angle ex-

tension, and a retainer engaging flange projecting from the extension.

In testimony whereof I affix my signature in presence of two witnesses.

SAMUEL T. WHITAKER.
